(57) **CLAIM**

The ornamental design for a food station, as shown and described.

DESCRIPTION

FIG. 1 is a perspective view of the food station showing our new design;

FIG. 2 is a front view thereof;

FIG. 3 is a back view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective of the food station of FIG. 1 shown with extended side trays.

Throughout the figures, where shown (i) the broken lines showing additional structure of the food station are for illustrative purposes only and form no part of the claimed design; (ii) the unshaded surfaces do not form part of the claimed design; and (iii) the dotted-dashed lines illustrate unclaimed boundaries of surfaces claimed as part of the design. Portions of the food station not shown in the Figures and not otherwise described in this specification do not form part of the claimed design,
